UNITED STATES PATENT OFFICE

EMIL O. H. POEPPEL, OF CHICAGO, ILLINOIS

CAN OPENER

Application filed March 30, 1931. Serial No. 526,258.

This invention relates to mechanical devices for opening cans, and particularly to the type of can opener having a rotary cutting disc adapted to travel around the periphery of the can immediately below the cap, for making a clean shear cut permitting the removal of the entire top of the can, and under the action of a serrated feeding disc adapted to be rotated by hand.

10 An object of this invention is to provide a can opener of this character having an improved form and arrangement of parts whereby a greater bearing surface is imposed on the top of the can, serving to more 15 properly guide the can opener during its operation, and prevent any inadvertent turning of the device in the operator's hand which might cause injury to the operator or produce a ragged edge on the can. It is also an 20 object to provide a device of this kind wherein the feeding disc can be rotated by a crank driven reduction gear, thereby imparting greatly increased power to the feeding disc without increase of effort on the part of the 25 operator and regardless of the pressure exerted by the operator on the handles.

Another object of this invention is to provide a device of this kind which is adapted for ready manual operation while held in 30 one hand without attachment to any support and without manually holding the can, and which is adapted to be used on cans of any cross sectional contour to remove the top of the can in a smooth, clean, even manner.

35 A specific embodiment of this invention is shown by the accompanying drawings, wherein:

Figure 1 is a plan view of the can opener as applied to a cylindrical can, the device 40 being in its closed or operative position.

Fig. 2 is a sectional view taken on line 2—2 of Fig. 4, showing the mounting plate in detail.

Fig. 3 is an enlarged section taken on line 45 3—3 of Fig. 1.

Fig. 4 is an enlarged section taken on line 4—4 of Fig. 1.

As herein illustrated, the improved can 50 opener is shown applied to a common form of can, comprising a cylindrical wall and a

cap, which are secured together by the usual upstanding seam.

The specific structure herein shown comprises a plate 5 having pivotally mounted thereon a handle 6, to which a lever 7 is pivotally fastened, the plate 5 supporting the driving assembly and the feed roller assembly, and the lever 7 supporting the cutting disc assembly.

In the form shown the plate 5 is provided 60 with a reinforcing bar 8 located diametrically across its center to provide additional strength at the points of greatest strain and additional support for the rotating elements journaled thereon. Both the plate 5 and the 65 reinforcing bar 8 are provided with registering slots 9—9.

The lever 7 is pivotally fastened at 10 across the handle 6 and carries at its inner end an arbor 11, extending through the slots 70 9—9, on which is mounted a cutting disc 12. With this arrangement a leverage action of the first order can be applied to the cutting disc 12 to initially force its cutting edge through the wall of a can, the motion of the 75 arbor 11 in the slots 9—9 being radial to the center of plate 5.

The arbor 11 is carried on the lever 7 by means of a stud 13, and is rigidly held in position by a nut 14 and washer 15. The cutting disc 12 is loosely mounted on the arbor 11 above the washer 15 so that it is free to rotate, and is also shown with a hub 16 on which a bearing member 17 is mounted so that it is 80 free to rotate independently of the cutting 85 disc 12.

The bearing member 17 may be, if desired, an enlargement of the hub 16. However, in that case the peripheral speed of the cutting edge would be greater than that of either the can or the bearing member, and the sliding friction of the cutting edge would cause it to rapidly become dull.

The feed roller assembly, as shown, comprises a threaded stub shaft 18 on which is fastened a driven gear 19 and a serrated feed roller 20 having an internally threaded hub 21. The hub 21 is journaled on the plate 5 and the reinforcing bar 8 through a bushing 100 22 having an annular shoulder 23 abutting

against the reinforcing bar 8 and swaged at 24 to hold the plate 5 and reinforcing bar 8 tightly together, and to secure the bushing 22 in position.

5 The feed roller 20 is located in the same plane as the bearing member 17 and cooperates with said bearing member 17 to grip the upstanding flange of a can, as shown in Fig. 4.

10 The driving assembly, as shown, is located adjacent the feed roller assembly and comprises a driving shaft 25, a driving gear 27 integral on said driving shaft and meshing with the driven gear 19 and a crank 26 fastened securely to said driving shaft. The driving shaft 25 is journaled on the plate 5 and reinforcing bar 8 through a bushing 28, and is held in position by a screw 29 and washer 30.

15 The bushing 28 is of the same shape and is mounted in the same manner as the bushing 22. In this way the plate 5 and reinforcing bar 8 are held securely together in two places.

20 The driving gear 27 is smaller than the driven gear 19 with which it meshes, the two forming a reduction gearing which greatly increases the power applied to stub shaft 18 and the feed roller 20.

25 In operation the improved can opener is held in one hand by the handle 6 and the lever 7, and the upstanding flange at the top of the can is gripped between the bearing member 17 and the serrated feed roller 20. By applying slight pressure to the handle 6 and lever 7, the cutting disc 12 is caused to penetrate the wall of the can at a point immediately below the can cap. With the can opener held in one hand, the crank 26 is rotated with the other hand so as to cause the can to rotate 30 under the driving action of the feed roller 20. While the can rotates in one direction the cutting disc 12 rotates in the opposite direction, making a clean cut around the entire can so as to permit the removal of the entire 35 cap.

40 The plate 5, being mainly over the top of the can, provides broad lateral bearing on the can top to prevent the device from twisting in the operator's hand, and also guides the device to make a clean, even cut. The round head of the screw 29 bears on the top of the can directly under the driving shaft 25, thus providing an inner bearing at the point of greatest thrust, serving to steady the device 45 while in operation.

45 Although but one specific embodiment of this invention is herein shown and described, it will be understood that numerous details of the construction shown may be altered or omitted without departing from the spirit of this invention as defined by the following claim.

I claim:

50 In a device of the class described, the combination of a plate having a slot, a reinforcing

ing bar mounted on said plate, having a slot to coincide with the slot of said plate, a handle pivotally attached to said plate, a lever pivotally fastened to said handle, an arbor attached to said lever and extending through said coinciding slots, a cutting disc mounted on said arbor, a bearing member on said arbor, a stub shaft journaled on said plate and reinforcing bar, a serrated feed roller mounted on said stub shaft in the same plane as said bearing member, a driven gear mounted on said stub shaft, a driving shaft journaled on said plate and reinforcing bar adjacent said stub shaft, a driving gear on said driving shaft meshing with said driven gear, and means for rotating said driving shaft.

Signed at Chicago this 27th day of March, 1931.
